UNITED STATES PATENT OFFICE.

EDWIN Q. BANGS AND WILLIAM ERNST, OF RACINE, WISCONSIN, ASSIGNORS TO HAMILTON BEACH MFG. CO., OF RACINE, WISCONSIN, A CORPORATION OF WISCONSIN.

MOTOR MOUNTING.

Application filed May 5, 1926. Serial No. 106,978.

This invention relates to improvements in motor mountings, adapted for the attachment of electric motors to sewing machine heads to hold the motor pulley wheels in 5 frictional engagement with the sewing machine hand wheels.

It is one of the objects of the present invention to provide a motor mounting for sewing machine heads arranged to throw the 10 motor into or out of engagement with the machine hand wheel.

A further object of the invention is to provide a motor mounting arranged to be locked in any adjusted position and away from the 15 hand wheel, if desired to permit bobbin winding.

A further object of the invention is to provide a motor mounting of the class described which is of very simple construction, is easily 20 secured to a sewing machine head, is strong and durable, and is well adapted for the purpose described.

With the above and other objects in view, the invention consists of the improved motor 25 mounting and its parts and combinations as set forth in the claim, and all equivalents thereof.

In the accompanying drawing in which the same reference characters indicate the same 30 parts in all of the views:

Fig. 1 is an end view of a sewing machine head equipped with the improved motor mounting and motor held thereby;

Fig. 2 is a side view thereof;

Fig. 3 is a view similar to Fig. 2 only showing the mounting and motor in an adjusted position of disengagement.

Referring now more particularly to the form of the invention shown in Figs. 1, 2 40 and 3 of the drawing, a sewing machine head is indicated by the numeral 8, and the same has a revolubly mounted hand wheel 9.

The side portion of the head is formed with a flattened portion 10 against which the upper portion of a vertical plate member 11 is secured by screws 12. The lower portion of said plate member 11 is off-set outwardly and rounded as at 13 and its outer surface is provided with serrations or teeth 14.

50 Adapted for adjustable attachment to the plate member 11, is a complementary plate member 15, widened at its upper portion to

permit the attachment thereto of a flat type electric motor 16 by screws 17. The lower portion of said plate member 15 is also rounded and its inner face is formed with serrations 18 to engage the serrations 14. A screw 19 is threaded through the serrated engaging portions of the members 13 and 15 to permit their being clamped in adjusted position.

The normal position of the device is as shown in Figs. 1 and 2 with the motor carrying plate 15 clamped in a vertical position, so that the motor pulley wheel 20 engages the hand wheel 9 to frictionally drive the same. 65 When it is desired to disengage the pulley wheel from the hand wheel, the screw 19 is loosened so that the member 15 may be turned to either side of its vertical center line and there clamped, as shown in Fig. 3. In this 70 position, the hand wheel is free for bobbin winding.

From the foregoing description, it will be seen that the improved motor mounting for sewing machine heads is of very simple and 75 novel construction, and is well adapted for the purpose set forth.

What is claimed as the invention is:

The combination with a sewing machine head having a motor mounting on one side 80 of the base of said head, and a hand wheel journaled in said head, of a motor having a friction wheel to drive said hand wheel, a plate having parallel end portions offset with 85 relation to each other, one of said end portions being rigidly secured to said mounting and the other end portion having a semi-circular serrated face, a second plate secured to one side of said motor and having a semi-circular serrated face at its free end to engage the serrated face of said first mentioned plate, a screw threaded through said plates above said serrated faces and adjustable to 90 clampingly hold the serrated faces of said plates in engagement for driving position, said second plate being freely movable on said first mentioned offset plate upon loosening of said screw, the offset portion of said first plate serving as a means of disengaging said serrated faces during adjustment.

In testimony whereof, we affix our signatures.

EDWIN Q. BANGS.
WILLIAM ERNST.
